US00D600413S

(12) United States Design Patent
Khubani

(10) Patent No.: US D600,413 S
(45) Date of Patent: * Sep. 15, 2009

(54) PET NAIL FILER

(75) Inventor: Ajit Khubani, Saddle River, NJ (US)

(73) Assignee: Telebrands Corp., Fairfield, NJ (US)

() Term: 14 Years

(21) Appl. No.: 29/308,861

(22) Filed: Jul. 10, 2008

(51) LOC (9) Cl. 30-99

(52) U.S. Cl. D30/158

(58) Field of Classification Search D30/158, D30/199; 119/600, 468, 607-611, 627, 633, 119/663, 601; D28/59, 36, 58, 44, 49, 50, D28/53, 85, 44.1, 51; D8/61, 62, 82, DIG. 7; D24/147, 146, 214, 215; D4/100-102; 132/73.6, 132/75.8, 76.4, 73.5, 75.3, 75.6, 76.5, 118, 132/119.1, 75.4, 75.5, 75; 30/29.5, 43, 43.4-43.6, 30/41.5, 206, 133, 26, 276, 29, 277.4, 240, 30/210, 43.92, 392, 167, 329, 169; 15/23, 15/28, 22.1, 101, 65, 104.04, 88, 104.095, 15/97.1, 179; 451/356, 162-164; 452/98; 81/3.42, 177.7, 57.26, 57.11, 58.3; 606/85, 606/131; 83/698.11, 520; 362/120; 206/368; 392/380, 384; 173/29, 217, 216; 310/50; 464/53; 601/70; D15/132; 433/133, 130, 433/125, 127, 166, 126, 132; 279/51, 147; D26/49, 37

See application file for complete search history.

(57) CLAIM

The ornamental design for a pet nail filer, as shown and described.

DESCRIPTION

FIG. 1 is a perspective view of a pet nail filer;

FIG. 2 is a back view thereof;

FIG. 3 is a front view thereof;

FIG. 4 is the first side view thereof;

FIG. 5 is the second side view thereof;

FIG. 6 is a top view thereof; and,

FIG. 7 is a bottom view thereof.

The broken lines in FIGS. 1-6 are for illustrative purposes and form no part of the claimed design.
